UNITED STATES PATENT OFFICE.

BARLOW BALDWIN, OF CHICAGO, ILLINOIS, ASSIGNOR, BY DIRECT AND MESNE ASSIGNMENTS, OF FOUR-TENTHS TO ERWALD S. HINTON AND TWO-TENTHS TO GEORGE A. HAMLIN, OF CHICAGO, ILLINOIS.

MERCURIAL AMALGAMATOR.

No. 823,577.

Specification of Letters Patent.

Patented June 19, 1906.

Application filed December 4, 1903. Serial No. 183,727.

To all whom it may concern:

Be it known that I, BARLOW BALDWIN, a citizen of the United States, residing at Chicago, in the county of Cook and State of Illinois, have invented a new and useful Mercurial Amalgamator, whereof the following is a specification.

My invention relates to that class of mercurial amalgamators which are primarily designed for extracting gold from auriferous earth, sand, or gravel without the use of water; and it has for its object the production of a machine that will be capable of forcing the auriferous material into and through a bath of mercury in such manner that the gold will be permitted to amalgamate with the mercury, while the waste material is floated and discharged from the surface of the mercury, whereby the completest possible extraction of the gold will be accomplished by the most economical means.

In the accompanying drawings, forming a part of this specification, Figure 1 is a side elevation of the machine. Fig. 2 is a view showing the same partly in longitudinal vertical section and partly in elevation. Fig. 3 is a sectional view and end elevation on the line 3 3 of Fig. 1, and Fig. 4 is a section on the line 4 4 of Fig. 3.

Like reference-numerals indicate like parts in all of the figures.

10 is the base of the machine, provided with uprights 11 11, which support a receptacle 12, into which the auriferous material is introduced through a funnel-like chute 13. The inner orifice of the chute 13 opens into a tubular screen 14, that is somewhat inclined from the horizontal and is secured to a rotary inclined shaft 15, which passes through 40 and forms the axis of said screen and is journaled in the end walls of the receptacle 12. The said shaft 15 is rotated by the crank 16, and the resultant rotation of the screen 14 causes the finer material to sift through said screen and into the tray 17, while the coarser waste is gradually advanced to and ejected from the lower end of the rotating screen into the waste-discharge 18. The lower part of the tray 17, into which the sifted auriferous

material falls, is provided with a screw conveyer 19, having the pulley 20 secured to one of its ends and actuated by the belt 21, passing over the pulley 22, that is secured to the crank-shaft 15 aforesaid. The rotation of the screw conveyer 19 forces the sifted auriferous material forward and out through the spout 23 into the secondary hopper-bottomed receptacle 24, and the latter is provided at its lower part with a second screw conveyer 25, secured to the shaft 26, actuated by the bevel-gears 27 27, connecting it with the crank-shaft 15. This second screw conveyer 25 by its rotation forces the auriferous material into and out through the spout of the hopper-bottomed receptacle 24 into the lower portion of the mercury-tank 28, and the material so forced out into the said tank is distributed and spread out therethrough by the rotary paddle 29, secured to the extreme lower end of the shaft 26 below the bottom orifice of the receptacle 24. When the auriferous material is thus distributed through the mercury-tank 28, the gold is taken up by and forms an amalgam with the mercury, while the waste material floats to the surface of the mercury and becomes heaped up thereon until the accumulation becomes sufficiently great to overflow the rim of the mercury-tank and fall upon the table or pan 30. This table or pan is movably swung from the bottom of the shelf 31, supporting the mercury-tank, and is kept in reciprocatory vibration by means of the link 32, which is connected, by means of the intermediate pivoted lever 33 and link 34, to the stud 35 on the pulley 20. The purpose of the vibration of this pan or table 30 is to shake off any superfluous accumulation of the waste material and present to the operator a film of said waste material of such relative thinness as to enable him to readily determine by casual inspection whether the auriferous material is being forced through the mercury at so rapid a rate as to cause granulation of the mercury and its adhesion to particles of the waste material floated up through it and thrown over the rim of the bath. The shelf 31, supporting the mercury-tank, is ad-

justed, by means of the set-screws 36 37 37, so as to allow the entire removal of the tank when it becomes desirable to retort the amalgam for the purpose of precipitating the gold.

5 By the foregoing mechanism and process it becomes possible to present even the finest particles of the gold contained in an auriferous mixture to the amalgamating action of the mercury without any loss at all comparable 10 to that necessarily incident upon the mercurial amalgamator processes heretofore practiced that consist, essentially, in blowing or scattering the auriferous mixture over the surface of mercury-baths or plates silvered with 15 mercury instead of forcing the entire bulk of the material to gradually pass through the mercury in such manner that the waste material is extracted by mere flotation. When the entire mass of the auriferous material is thus 20 forced into the bottom of a bath of mercury, no part of that material can come to the surface except by flotation, and if the material is thus gradually forced into and distributed through the bottom of the bath practically 25 all of the contained particles of gold will be presented to the amalgamating action of the mercury, and no considerable part of the mercury will be granulated and carried to the surface of the bath by the flotation of the 30 waste. The distribution at the bottom of the bath is effected by a nearly plane or slightly paddle-form rotary distributer so shaped that it may spread the material out over the bottom of the tank with the least 35 possible stirring or agitative effect upon the mercury, any such stirring or agitation having a tendency to cause sufficient granulation of the mercury to wholly defeat the practicability of the process and it being essential 40 that the distribution of the material should consist merely in spreading it out as thinly as possible over the bottom of the tank without attempting to stir it into or otherwise force it into mechanical mixture with the mercury, 45 and the mechanism here provided for forcing the auriferous material into the mercury is of such character that the use of water is dispensed with, and yet material of very various character and consistency, whether finely 50 pulverized or coarsely granular, is worked without stoppage or clogging of the conveyer that forces it into the amalgamating-tank.

This process makes possible the operation of deposits of auriferous earth and sand in 55 regions where water is unobtainable, and the simplicity of the mechanism makes it readily transportable and capable of being set up and operated by the most unskilled labor.

My invention as hereinabove set forth is 60 embodied in certain particular and preferable forms of construction; but I do not limit myself to such special forms or to less than

all the possible forms in which the invention as hereinafter claimed may be embodied.

I now claim—

1. In a mercurial amalgamator, in combination, a tank for the mercury, a hopper for dry auriferous material, a spout extending from said hopper into said tank, and a conveyer adapted to drive the aforesaid material 70 into and through said spout without clogging thereof, and a nearly plane horizontal distributer adapted to spread said material over the bottom of said tank without agitative stirring of the mercury, substantially as specified. 75

2. In a mercurial amalgamator, in combination, a tank for the mercury, a hopper for dry auriferous material, a spout extending from said hopper into said tank, and a screw 80 conveyer adapted to drive the aforesaid material into and through said spout without clogging thereof, and a nearly plane horizontal distributer adapted to spread said material over the bottom of said tank without agitative stirring of the mercury, substantially as specified. 85

3. In a mercurial amalgamator, in combination, a tank for the mercury, a hopper for dry auriferous material, a spout extending from said hopper into said tank, a conveyer 90 adapted to drive the aforesaid material into and through said spout without clogging thereof, and a nearly plane horizontal paddle adapted to spread said material over the bottom of said tank without agitative stirring of the mercury, substantially as specified. 95

4. In a mercurial amalgamator, in combination, a tank for the mercury, a hopper for dry auriferous material, a spout extending from said hopper into said tank, a screw conveyer adapted to drive the aforesaid material into and through said spout without clogging thereof, and a nearly plane horizontal paddle adapted to spread said material over the bottom of said tank without agitative stirring of the mercury, substantially as specified. 105

5. In a mercurial amalgamator, in combination, a tank for the mercury, a hopper for dry auriferous material, a spout extending from said hopper into said tank, and a conveyer extending through said hopper and said spout and adapted to drive the aforesaid material out of the said hopper and into and 110 through said spout without clogging thereof, and a nearly plane horizontal distributer adapted to spread said material over the bottom of said tank without agitative stirring of the mercury, substantially as specified. 115

6. In a mercurial amalgamator, in combination, a tank for the mercury, a hopper for dry auriferous material, a spout extending from said hopper into said tank, and a screw 120

conveyer extending through said hopper and said spout and adapted to drive the aforesaid material out of the said hopper and into and through said spout without clogging thereof, 5 and a nearly plane horizontal distributor adapted to spread said material over the bottom of said tank without agitative stirring of the mercury, substantially as specified.

In testimony whereof I have hereunto set my hand in the presence of two subscribing ^{to} witnesses.

BARLOW BALDWIN.
